UNITED STATES PATENT OFFICE.

HEINRICH DREWELL, OF CHARLOTTENBURG, GERMANY.

TYPE-SETTING MACHINE.

1,163,985.

Specification of Letters Patent. Patented Dec. 14, 1915.

Application filed April 16, 1913. Serial No. 761,427.

To all whom it may concern:

Be it known that I, HEINRICH DREWELL, subject of the German Emperor, residing at Charlottenburg, Germany, have invented 5 new and useful Improvements in Type-Setting Machines, of which the following is a specification.

The principal object of the present invention consists in means for automatically interrupting the actuation of an automatically operated composing machine in case of trouble occurring in the assembling of matrices or types, the assembling device being obstructed for instance. For this purpose a 10 stopping device is actuated if a movable member, the movement of which corresponds with the increasing length of a line of matrices or types being set up, which member may be termed as the line-controlling member, remains at rest for a certain 15 time although a certain number of matrix or type delivering devices have been operated during this time. As, however, certain delivering devices, for example those delivering the word separating blanks, or an "e", 20 an "n" or any other character which occurs frequently, are operated repeatedly in most every line, it is sufficient to control the stopping device by means of one of these delivering devices in connection with the line 25 controlling member in order to limit the number of matrices or letters possibly released after a trouble occurs until the machine is stopped.

In the hereafter described embodiment 30 of my invention I prefer to control the stopping device by means of the device delivering the word separating blanks into the line. It is supposed that two such blanks 35 are not used without one or more characters inserted between them. Now, if the line-controlling member has not moved since a certain operation of said blank delivering device and the latter is operated again, 40 something in the machine must be out of order and the stopping device is therefore operated in such cases.

In the drawings is shown an embodiment 45 of this invention in combination with the assembling device of the well known matrix-setting and line-casting machine of the Mergenthaler system. It is supposed that this machine is automatically operated by means of a perforated band for example in the 50 manner described in my U. S. Letters Patents 864,519 dated August 27, 1907 and

915,748 dated March 23, 1909, and in my co-pending application Serial Number 691,100, filed April 16, 1912.

Figure 1 shows the mechanical part of 60 the device, Fig. 2 is a diagram of the electrical connections, Fig. 3 shows the device for re-actuating the composing machine, and Fig. 4 shows the switching device controlling the operating electric current of the machine. 65

In Fig. 1 the line-resistant 1 supporting the matrices or letters and keeping them from being thrown down, is fastened on the slide 2 which is suitably guided in the main 70 frame of the machine. With the slide 2 is connected a rack 3 provided with small ratchet teeth on its upper edge. Above the rack is a lever 4 swinging around the neck-screw 5 and bearing an easily rotatable 75 three-armed lever 6. Acted upon by a spring 7 this lever tends to lean with its lever-arm 8 against the pin 9 on the lever 4. The lever-arm 10 of the lever 6 is pressed downward by the end of a pawl 11, which 80 is rotatably fastened on a movable plate 12.

A spring 13 acting upon a short arm of the pawl 11 tends to push this pawl against a pin 14 fastened on the plate 12. By means of a neck-screw 15 the plate 12 is rotatably 85 fastened on a short lever 16 swinging around the neck-screw 17. At the upper end of the plate 12 is fastened a rod 18, which is connected with a lever 19. This lever is pivoted by a neck-screw 28 to the main 90 frame of the machine and is connected with a releasing rod 20. This rod is rocked and the lever 19 turned in corresponding manner when a certain key, in the present case the key for releasing space-bands is struck. 95 The device for lifting the rod 20 and for striking the corresponding key is for example fully shown and described in the drawings and specification of my U. S. Letters Patent 864,519, dated Aug. 27, 1907. 100 As described before it is advantageous to choose for this purpose the key serving for releasing and inserting the space-bands or "wedge-shaped justifiers." When the rod 20 and the lever 19 have returned into their 105 lower positions, the pawl 11 leans upon the lever arm 10 of the small lever 6, which acted upon by the spring 7 has turned during the lifting of the lever 19 and the plate 12 so far that its arm 8 touches the pin 9, 110 while the lower arm 22 engages with the teeth of the rack 3. The lever 4 is acted

upon by the tension-spring 23 and the plate-spring 24, which lies upon a projection 25 of insulating material at the end of the lever 4. The leaf-spring 24 tends to press 5 the lever 4 down, though usually it is drawn up by the stronger spring 23, which causes the spring 24 to be pressed against the opposite contact-screw 26. If however the pawl 11 leans, as described before, upon the lever-arm 10, the lever 4 is pressed downward by 10 the stronger spring 21 operating the rod 20, and the contact between the screw 26 and the plate-spring 24 is opened. At the same time the lever-arm 22 of the lever 6 engages 15 with the rack 3.

If the length of the line increases by matrices or letters being inserted, the line-resistant 1 with its slide 2 is moved in the direction of the arrow 27 and the rack 3 takes 20 the point of the lever 22 along thereby turning the lever 6 and withdrawing the lever-arm 10 from the pawl 11. Consequently the influence of the spring 21 upon the lever 4 ceases and therefore the latter is pulled 25 upward by the spring 23 and the spring 24 touches the contact-screw 26. But if the length of the line does not change any more after the contact between the screw 26 and the spring 24 has been interrupted, *e. g.* if 30 no more letters or matrices get into the line, causing the lever-arm 10 and also the lever 4 to be released from the pawl 11 or the spring 21, the composing machine is caused to stop as soon as the space-band key is operated 35 again. For this purpose there is provided the connection shown in Fig. 2. The numerals 31 and 32 indicate the spring-pressed levers operated by the two holes of the perforated register-band, which constitute 40 the space-band symbol. The pointed ends of the levers are pressed against the register-band, the other ends carrying contact-screws 33 and 34 which tend to contact with the opposite metal pieces 35 and 36. The levers are connected with one pole 45 of a source of current 37. The metal-piece 35 is connected with the coil of an electromagnet 38. From there another connection 39 leads to the other electric devices of the machine. Over a switch-lever 40, a contact-spring 41 attached to the latter, and a contact-screw 42, the connection 39 is connected 50 with the other pole of the source of current 37. The switch-lever 40 is acted upon by the pawl 43, keeping it in its rest-position and so causing the spring 41 to contact with the screw 42. If the pawl 43, constituting the armature of the electromagnet 58, is attracted by the latter, the contact is opened at 55 means of a spring 44 acting upon the switch-lever 40, and the current actuating the composing machine is interrupted.

If the levers 31 and 32 enter two holes in the perforated band at the same time and 60 cause the screws 33 and 34 to touch the

metal pieces 35 and 36, the electromagnet 38 actuates the switch-lever 45 and causes it to contact with a screw 46, thereby closing the circuit of an electromagnet 47, this electromagnet serves for inserting the space-bands. The circuit of this electromagnet 70 contains the screw 26 and the leaf-spring 24, two other electromagnets 48 and 49, actuating the switch-levers 50 and 51, belonging to a shunt-circuit parallel to the contact-spring 24 and the contact-screw 26. As long as the spring 24 contacts with the screw 26, a current flowing through the electromagnet 47 causes the space-band to be released. But if the levers 31 and 32 touch 80 their metal pieces 35 and 36 respectively, closing the circuit of the electromagnet 47, while the contact between the spring 24 and the screw 26 is opened besides the coil of electromagnet 47 the coils of electromagnets 85 48 and 49 are energized, the latter being now in series with the electromagnet 47 and diminishing by their resistance the current of the electromagnet 47 so as to prevent it to become operative. The levers 50 and 51, 90 however, are switched in this case. These levers are connected with the poles of an electromagnet 52, serving for stopping the register-band after a line has been set and for actuating the device for transporting the 95 line. The operation of this electromagnet is fully described in my before-mentioned co-pending application Serial No. 691,100 filed April 16, 1912. In their rest positions the levers 50 and 51 lean against the screws 53 100 and 54, which are connected with the main-circuit of the composing machine, and by means of the register-band cause the electromagnet 52 to be energized when a certain 105 perforated symbol of the band becomes operative. After having been switched the levers 50 and 51 contact with the screws 55 and 56, one of which is connected directly with the pole of the source of current 37, the other leading to the other pole over the 110 coil of the electromagnet 58. If the levers 50 and 51 are switched because of the electromagnets 48 and 49 being energized, the electromagnets 52 and 58 are directly connected with the two poles of the source of current 115 37 and therefore are actuated. The electromagnet 52 acts upon the device for stopping the register-band and electromagnet 58 acts upon the pawl 43, withdrawing it from the end of the lever 40. Consequently the main 120 circuit is interrupted between the spring 41 and the screw 42. When the lever 40 begins to move the spring 41 remains on the contact screw 42 for a short time, although long enough to allow the electromagnet 52 to be 125 properly energized and to become operative before the main circuit is interrupted. It may be seen therefore, that the actuation of the composing machine is interrupted, *e. g.* the register-band is stopped and the main-

circuit is interrupted, if a space-band symbol acts upon the levers 31 and 32 while the spring 24 does not contact with the screw 26.

For re-actuating the machine after the trouble has been removed the lever 40 must be caught by the pawl 43. This is done by means of the device described hereafter.

The register-band is guided partly by a frame 61 rotatably mounted on the shaft 60 (Fig. 3), as more particularly described in my before-mentioned co-pending application. The frame is lifted for introducing the register-band and then replaced into its horizontal position shown in Fig. 3 in dotted

15 lines. The shaft 60 has a projection 62 acting upon an angle-lever 63, 64. At the arm 64 of the latter is fastened a rod 65, carrying a finger 66, adapted to act on the lever 40 of the main switch. When the frame is 20 opened, the projection 62 releases the angle-lever 63, 64, and the rod 65 moves downward on account of its weight or compelled by a suitably attached spring and by means of its finger 66 causes the lever 40 to be caught 25 by the pawl 43.

The working method of the here described device can be shortly interpreted as follows: Each time the space-band key is used, the rod 18 with its pawl 11 presses upon the lever 10 or 4 and the contact between the screw 26 and the spring 24 is opened. The matrix following next to the space-band causes the contact to be closed again by pushing forward the slide 2 with the resistant 1. If 35 suddenly there are no more matrices assembled into the slide because of the entrance being obstructed or such like, the next space-band symbol of the register-band opens the contact and the following one stops the 40 action of the machine. The number of matrices released from the magazine in the meantime is limited by the frequent occurring space-bands. After the trouble has been removed, the frame 61 is opened and the register-band drawn back far enough to re-set the 45 same line. The opening of the frame 61 causes the main circuit to be closed again.

As stated above one of the frequent occurring letters like "e" or "n" can also be 50 used for the purpose described above instead of the space-band.

The device can also be used without any essential alteration in combination with type-setting machines since in these too there 55 is or can be applied a member, which moves with the progressing length of the line corresponding with the slide 2. Besides this movement the device requires nothing but a rocking movement of the rod 18 caused by 60 the insertion of a special, frequent occurring type or its equivalent.

What I claim as my invention and desire to secure by Letters Patent is:

1. In means for automatically operating 65 composing machines the combination of a

line-controlling member, adapted to advance corresponding with the increasing length of the line being set up with a delivering-controlling member repeatedly operated during the setting of a line of matrices, types or 70 blanks, a stopping device for interrupting the actuation of the composing-machine, intermediate means adapted to be actuated by said delivering controlling member and when actuated engaging said line-controlling member and operatively connecting means between said intermediate means and said stopping device adapted to actuate the latter. 75

2. In means for automatically operating 80 composing machines, the combination of a line-controlling member adapted to advance corresponding to the increasing length of a line being set up, delivery means controlling the delivery of a matrix, type or blank into 85 the line, stop means adapted to stop the operation of the composing machine when actuated, preparatory means preparing the actuation of said stop means when being in their preparatory position, and preventing the actuation of said stop means when being in 90 their normal position, means for bringing said preparatory means into their preparatory position and actuated by said delivery means, means for bringing said preparatory 95 means from their preparatory position into their normal position and actuated by said line-controlling member when advancing, operating means for operating said stop means and adapted to be actuated by or with 100 said delivery means while said preparatory means are in their preparing position.

3. In means for automatically operating 105 composing machines, the combination of a line-controlling member adapted to advance corresponding to the increasing length of a line being set up and carrying a toothed rack, a stopping device, adapted to stop the operation of the composing machine, an intermediate member adapted to engage said rack 110 on said line controlling member when actuated and to be disengaged therefrom when said line controlling member advances, matrix-, type-, or blank-delivering means adapted to actuate said intermediate member, 115 operatively connecting means between said intermediate member and said stopping device adapted to actuate the latter and to be operated when said intermediate member is actuated while already engaging said rack 120 on said line-controlling member.

4. In means for automatically operating 125 composing machines the combination of a line-controlling member adapted to advance corresponding to the increasing length of a line, delivery means controlling the delivery of a matrix, type or blank, an intermediate member adapted to engage said line-controlling member when actuated by said delivery means and to be disengaged by the forward 130

- movement of said line-controlling member, a stopping device adapted to stop the action of the machine when operated, preparatory means adapted to be brought into preparatory position by said intermediate member when engaging said line-controlling member thereby preparing the actuation of said stopping device, and stop device operating means, adapted to be actuated by said delivery means when said preparatory means are in their preparatory position.
5. In means for automatically operating composing machines the combination of a line-controlling member, the position of which corresponds with the increasing length of the line being set up, with a to and fro moving rod, operated each time a specimen of a certain kind of frequent occurring matrices, letters or such-like is inserted, a spring-contact opened by the action of said rod and re-closed each time the said line-controlling member moves thereafter, and an electrical switching device caused to interrupt the main-circuit of the composing machine if the contact has not yet been closed when the next specimen of said kind of matrices or such-like occurs.

6. In combination with a composing machine adapted to be operated by perforated bands, guide means for guiding the perforated band and comprising a guiding frame to be opened for introducing the band, an electric circuit for operating the machine by means of the perforated band, a switch-lever holding said electric circuit closed, when in its operative position, a line-controlling member the position of which corresponds with the increasing length of the line being set up, means for controlling said switch lever by said line-controlling member and bringing said switch lever into its inoperative position, thereby interrupting said electric circuit, and operatively connecting means between said guiding frame and said switch lever for restoring said switch lever to its operative position by said guiding frame.

In testimony whereof I have signed my name to this specification in the presence of two subscribing witnesses.

HEINRICH DREWELL.
